UNITED STATES PATENT OFFICE.

REINHARD HILDEBRAND, OF WEBSTER GROVES, MISSOURI.

CYLINDER-HEAD FOR INTERNAL-COMBUSTION ENGINES.

1,376,620.

Specification of Letters Patent.

Patented May 3, 1921.

Application filed December 4, 1919. Serial No. 342,371.

To all whom it may concern:

Be it known that I, REINHARD HILDEBRAND, a citizen of Germany, a resident of Webster Groves, in the county of St. Louis and State of Missouri, have invented certain new and useful Improvements in Cylinder-Heads for Internal-Combustion Engines, of which the following is a full, clear, and exact description, reference being had 10 to the accompanying drawings, forming a part of this specification.

This invention relates to improvements in cylinder heads for internal combustion engines, the invention being especially adapted 15 for use in very large internal combustion engines of the Diesel type, wherein the ignition is effected by compressing air to about 500 lbs. pressure per square inch, thereby producing a temperature of about 1000° F. 20 The temperatures resulting from combustion usually range from about 2000° F. to 2500° F. Actual experience has shown that comparatively small Diesel engines of less than a few hundred horse-power can be carefully 25 designed to withstand the stresses resulting from higher pressures and high temperatures, and it may appear that much larger engines could likewise be readily designed by merely copying the smaller designs, but 30 this is not true. In fact, the very large Diesel engines have never been entirely successful. Their cylinder heads have not withstood severe stresses resulting from the intense heat and high pressure in the combustion 35 chambers, this being especially true of engines having cylinders larger than 26 to 30 inches in diameter. As a consequence, very large engines of the Diesel type, although highly economical so far as fuel is 40 concerned, have not come into general use.

The cylinder heads of small engines form the top walls of comparatively small combustion chambers, and by cooling these small heads injurious stresses can be avoided, but 45 in a much larger engine, the combustion space is very large in comparison with the cooling surfaces of the walls of the combustion chamber, and owing to the increase in volume of the fuel without a corresponding 50 increase in cooling area, the walls of the large combustion chambers are subjected to comparatively high temperatures. Furthermore, the large combustion chamber is relatively high and very intense heat is generated at the center of the combustion cham-

ber, as well as at the center of the cylinder head forming the top wall thereof.

Owing to the extremely high temperatures at the central portions of large cylinder heads, and the lack of opportunity for proper cooling, the cylinder heads of large Diesel engines eventually crack near the center. Heat variations cause expansion and contraction of the cylinder head which is a complex casting containing valves and subjected to high pressures, and great difficulty has therefore been experienced in designing large cylinder heads capable of withstanding even a brief period of service. The difficulties of this problem are fully appreciated 60 by engineers familiar with Diesel engines, and the failure to produce very large engines of this type adapted to stand the heat and pressure without breakage in the cylinder heads clearly shows that there must be 65 some unusual difficulties preventing a solution of this particular problem. I will, therefore, briefly point out conditions existing in cylinder heads of this kind, and endeavor to show why the stresses do not result in breakage of my cylinder head.

The ordinary type of cylinder head has a central portion opposing the engine piston and exposed directly to the high pressures and intense heat resulting from combustion 70 in the cylinder. This highly heated central portion is usually surrounded by a water-cooled marginal portion seated upon the top of the cylinder. Obviously, the water cooled margin tends to prevent expansion of the 75 central portion, but the fire-heated central portion must expand, and as a result the large cylinder heads eventually crack near the center, as will be hereafter pointed out. If the cylinder head could, during actual 80 running of the engine, be heated uniformly, and if it were free to expand and contract, there would be no severe stresses due to heat. With this ideal condition in view, my object 85 is to eliminate stresses which have heretofore resulted in fractures in large cylinder heads.

Figure I is a top view, partly in section, on the line I—I, Fig. II, showing a cylinder head embodying the features of this invention.

Fig. II is a section on the line II—II, Fig. I, showing the cylinder head applied to a cylinder.

Fig. III is a section on the line III—III, Fig. I.

105

110

Fig. IV is a diagrammatical view showing the heat-exposed face of the cylinder head.

Fig. V is a diagrammatical vertical section, showing the head applied to a cylinder.

5 1 designates the cylinder of an internal combustion engine, and 2 designates a piston adapted to reciprocate in the cylinder. To illustrate one form of the invention, I have shown a hollow cylinder head in the form 10 of a single casting having a bottom wall E, side walls 3 and a top wall 4, all integrally connected together. Ports 5 are formed in the side walls 3 for the admission and discharge of cooling fluid, preferably water, 15 which passes through the hollow cylinder head as suggested by arrows in Fig. II. The bottom of the cylinder head is only slightly larger than the internal diameter of the cylinder, and the marginal edges of this bottom 20 are seated upon the top face of the cylinder. Vertical bolts 6 detachably secure the cylinder head to the cylinder. The upper portion of the head is extended to receive the bolts, or studs, which lie entirely 25 beyond the heat-exposed lower portion of the head, said lower portion being free to expand in response to the action of heat generated in the combustion chamber.

The Diesel engine head is provided with 30 the usual inlet port 7 for the admission of air, exhaust port 8 for the discharge of products of combustion, and injector 9 whereby fuel is injected into the combustion chamber. To receive the injecting device an 35 opening is formed in the center of the bottom wall E, at a point directly between the inlet and exhaust ports, which are preferably formed in said bottom wall. A tube 9' surrounds the fuel injecting device, said tube 40 being secured as shown in Fig. II.

Theory and actual experience show that the ordinary large cylinder head cracks in the direction A—B (Fig. IV), this being the typical "Diesel head crack." It is generally termed a "heat crack," for the 45 stresses due to heat greatly exceed those due to pressure. While the engine is running, both of these stresses vary constantly, fluctuating in wide limits. After each ignition follows a rapid rise in temperature and consequently an increase in stress up to a maximum. Then follows a decrease, down to minimum until the compression stroke begins, when the temperature and consequently 50 the stresses begin to increase. The fibers of the metal, therefore, are continually elongating and contracting, and if the fibers thus affected are not permitted to yield freely, they will eventually fail as a result of "fatigue," which produces the typical "Diesel 55 head crack."

The ordinary Diesel head is a hollow casting having central portions exposed directly to the heat generated in the combustion 60 chamber, and these heat-exposed portions

are surrounded by relatively cool marginal portions not directly exposed to the burning fuel. The marginal portions of the ordinary head are not only protected from direct action of the fire, but they are also cooled by 70 water circulating through the cylinder head. It is obvious that the central portions of the cylinder head bottom, being exposed directly to the fire, must expand, and if such expansion is effectively resisted, or prevented, destructive stresses are bound to occur. In the ordinary cylinder head having water-cooled margins protected from direct action of the fire, these relatively cool margins may be compared to a non-yielding collar shrunk onto the heat-exposed central portions, and they very effectively oppose expansion of the central portions. Obviously, the heat-exposed central portions cannot 75 freely expand if they are surrounded by an 80 integral non-expanding marginal portion. 85

Some advantage may be gained by making the cylinder head only slightly larger than the internal diameter of the cylinder, but this alone would not eliminate the destructive stresses due to a comparatively cool or "non-expanding" marginal portion. 90

Since the ordinary cylinder heads crack in the direction A—B (Fig. IV) and not in the direction C—D, it is evident that the 95 stresses in the direction C—D are greater than in the direction A—B, for a rupture due to tensile or compression stresses is always approximately at a right angle to the stress. In the ordinary head, with a comparatively "non-expanding" margin, it appears that expansion in the direction C—D is very firmly opposed by the resistance at the margin, while in the direction A—B some expansion is permitted at the inlet and 100 exhaust ports. The metal at these ports is yielding not only because the walls of the ports can be forced to a slightly oval form, but primarily because it is cooled at these points, and thus contracted, by the comparatively cool exhaust gases passing through one port and by the cold air passing through the other. I, therefore, believe it is especially desirable to relieve the stresses in the direction C—D. 105

Attention is now directed to Fig. I and to the diagrammatical view (Fig. IV) which show that the water-receiving chamber is elongated in the direction A—B. Some expansion in this direction is permitted by 110 physical displacement of the metal forming the ports, and by the cooling action of incoming and outgoing fluids tending to cause contraction of the metal forming the walls of the ports. However, we are faced with 115 the problem of preventing destructive heat stresses in the direction C—D. The central portions of the bottom wall E are exposed directly to the heat resulting from combustion, and since both theory and actual prac- 120

tice show that these central portions are more intensely heated than the margins, I expose said central portions to the direct action of the cooling water. The marginal 5 portions M, at opposite sides of the central portions, are exposed to heat transmitted from the combustion chamber, but not to the direction action of the cooling water. Therefore, the marginal portions on the line 10 C—D will freely expand in response to the action of the heat, thereby permitting and aiding expansion of the central portions in the direction C—D. Instead of preventing expansion by the use of an integral non- 15 expanding margin around the heat exposed central portions, I have herein disclosed expanding marginal portions which coöperate with the central portions to permit expansion thereof, so as to eliminate stresses 20 which have heretofore caused the typical "Diesel head cracks."

Another advantage of the elongated, or oval, water chamber as compared with a circular one, lies in the fact that the oval 25 wall can yield more easily in response to the expansion of the heat-exposed wall, but it is to be understood that the invention is not limited to a cooling chamber of any particular shape, nor to any particular means 30 for cooling the cylinder head. Although I have shown inlet and exhaust ports in the cylinder head, it will likewise be understood that such ports may be formed at any suitable points in the engine. I am 35 also aware that various modifications within the scope of the claims hereunto appended will suggest themselves to those skilled in the art.

The cylinder head I have shown to illustrate the invention has a bottom wall exposed 40 directly to the heat generated in the combustion chamber. This bottom wall has expanding central portions from which heat is rapidly transmitted to prevent undue expansion thereof. Marginal portions of the 45 bottom wall are exposed to the heat, but not to the direct action of the cooling medium, so these heat-retaining expanding margins permit expansion of the expanding central 50 portions. The heat-retaining margins M are preferably in the form of flanges extending from opposite sides of the water-receiving chamber so as to overlap the top of the cylinder, as shown in Figs. II and V. The 55 attaching bolts 6 do not prevent expansion of the margins. The cooling device may be termed a "differential" cooling means, for it acts directly upon the heat-exposed central portions, but only indirectly upon the 60 heat-exposed marginal portions M, said marginal portions being comparatively uncooled, so as to expand freely in response to the heat.

The side walls 3 of the water-receiving 65 chamber are located directly above the

piston, where they serve as effective reinforcing means for the cylinder head. Heretofore, such walls have been located entirely over the cylinder, instead of over the piston. In Figs. II and V it will be seen that the 70 stresses resulting from tightening of the nuts 6', or from the pressure in the cylinder, are transmitted through the walls 3 which overlie the combustion chamber, said walls 3 serving as compression members which are 75 well adapted to withstand and transmit the stresses.

I claim:

1. An internal combustion engine having a cylinder head comprising a bottom wall, a 80 top wall and a single continuous side wall, the bottom wall projecting beyond said side wall.

2. An internal combustion engine having a cylinder head provided with top and bottom walls and a wall connecting the same, the area inclosed by the bottom of said connecting wall being smaller than said bottom wall and substantially in the form of an oval. 85

3. An internal combustion engine provided with a combustion chamber and a cylinder head, said cylinder head having expanding central portions from which heat is rapidly transmitted to prevent undue expansion thereof, said cylinder head also having heat-retaining expanding marginal portions 90 permitting expansion of said expanding central portions, said heat-retaining expanding marginal portions being directly exposed to heat generated in the combustion chamber so as to expand in response to the action of the heat, and fastening means for the cylinder head permitting expansion of 95 said heat-retaining expanding marginal portions. 100

4. In an internal combustion engine, a cylinder provided with a combustion chamber, and a cylinder head seated on said cylinder, said cylinder head having expanding central portions exposed directly to the heat 110 of the combustion chamber, cooling means acting directly upon said expanding central portions to prevent undue expansion thereof, said cylinder head having comparatively uncooled heat-retaining expanding marginal 115 portions permitting expansion of the cooled central portions, said heat-retaining expanding marginal portions of the cylinder head being directly exposed to the heat generated in the combustion chamber so as 120 to expand freely in response to the action of the heat, and fastening means permitting expansion of said comparatively uncooled marginal portions of the cylinder head. 125

5. An internal combustion engine provided with a combustion chamber and a cylinder head, said cylinder head having expanding central portions exposed directly to the heat of the combustion chamber and cooling means comprising a water-receiving 130

chamber over said expanding central portions, said expanding central portions being exposed directly to the water to provide for rapid transmission of heat therefrom, said 5 cylinder head having relatively uncooled heat-retaining expanding marginal portions directly exposed to the heat generated in the combustion chamber so as to expand freely in response to the action of the heat, and 10 fastening means whereby said cylinder head is secured to permit free expansion of said relatively uncooled heat-retaining marginal portions.

6. An internal combustion engine provided with a cylinder forming a combustion chamber, a cylinder head seated on and closing one end of said cylinder and provided with a bottom wall, said bottom wall having expanding central portions exposed directly to the heat of the combustion chamber, cooling means including a water-receiving chamber formed over said expanding central portions to prevent undue expansion thereof, said bottom wall also having relatively uncooled heat-retaining expanding marginal portions directly exposed to the heat generated in the combustion chamber so as to expand freely in response to the action of the heat, and fastening means whereby said cylinder head is secured to permit free expansion of said relatively uncooled heat-retaining marginal portions of said bottom wall.

7. An internal combustion engine having a combustion chamber and a cylinder head, said cylinder head having cooling means including an elongated water-receiving chamber narrower than the cylinder head, the bottom wall of said elongated water-receiving chamber being exposed directly to the heat of the combustion chamber so as to expand in response to the action of the heat, said cylinder head also having relatively uncooled heat-retaining expanding marginal portions exposed to heat transmitted from said combustion chamber so as to expand freely in response to the action of the heat, and said heat-retaining expanding marginal portions being located at opposite sides of 45 said elongated water-receiving chamber to permit expansion of said bottom wall.

8. An internal combustion engine having a combustion chamber and a cylinder head, said cylinder head having cooling means including an elongated water-receiving chamber narrower than the cylinder head, the bottom wall of said elongated water-receiving chamber being exposed directly to the heat of the combustion chamber so as to expand 55 in response to the action of the heat, said cylinder head also having relatively uncooled heat-retaining expanding marginal flanges exposed to heat transmitted from said combustion chamber so as to expand 60 freely in response to the action of the heat,

and said heat-retaining expanding marginal flanges being located at opposite sides of said elongated water-receiving chamber to permit expansion of said bottom wall.

9. An internal combustion engine having a combustion chamber and a cylinder head, said cylinder head having cooling means including an elongated water-receiving chamber narrower than the cylinder head, the bottom wall of said elongated water-receiving chamber being exposed directly to the heat of the combustion chamber so as to expand in response to the action of the heat, said bottom wall being provided with a valve port, said cylinder head having relatively uncooled heat-retaining expanding marginal portions exposed to heat transmitted from said combustion chamber so as to expand freely in response to the action of the heat, and said heat-retaining expanding marginal portions being located at opposite sides of said elongated water-receiving chamber to permit expansion of said bottom wall.

10. An internal combustion engine provided with a cylinder forming a combustion chamber, and a cylinder head consisting of a single casting secured to and seated on one end of the cylinder, the bottom of said cylinder head being substantially as large as the diameter of its seat, said cylinder head having cooling means including an elongated water-receiving chamber narrower than the cylinder head, the bottom wall of said elongated water-receiving chamber being formed integral with said cylinder head, and said bottom wall being exposed to the heat of the combustion chamber so as to expand in response to the action of the heat, said bottom wall of the elongated water-receiving chamber being provided with an air inlet port and an exhaust port, said cylinder head having relatively uncooled heat-retaining expanding marginal portions exposed to heat transmitted from said combustion chamber so as to expand freely in response to the action of the heat, and said heat-retaining expanding marginal portions being located at opposite sides of said elongated water-receiving chamber to permit expansion of said bottom wall.

11. An internal combustion engine provided with a cylinder, a piston in said cylinder, a hollow cylinder head having a top wall, side walls and a bottom wall seated on said cylinder, said side walls being located directly above the piston and said bottom wall being extended from the side walls to overlap the cylinder, and fastening means whereby stresses are transmitted through said side walls to force the cylinder head onto the cylinder.

In testimony that I claim the foregoing I hereunto affix my signature.

REINHARD HILDEBRAND.
